DESIGN FOR A SPONGE BASKET

Walter E. Heinecke, Chicago, Ill., assignor to James A. Rhodes & Company, Chicago, Ill., a corporation of Illinois

Application June 27, 1936, Serial No. 63,525

Term of patent 7 years

To all whom it may concern:

Be it known that I, Walter E. Heinecke, a citizen of the United States, residing at Chicago, in the county of Cook and State of Illinois, have invented a new, original, and ornamental Design for a Sponge Basket, of which the following is a specification; reference being had to the accompanying drawing, forming a part thereof.

In the drawing the figure is a perspective view of a sponge basket showing my new design.

I claim:

The ornamental design for a sponge basket, as shown.

WALTER E. HEINECKE.
